UNITED STATES PATENT OFFICE

MILLARD B. LUCKER, OF BENTON HARBOR, MICHIGAN, ASSIGNOR, BY MESNE ASSIGNMENTS, TO THE DAYTON MALLEABLE IRON COMPANY, OF DAYTON, OHIO, A CORPORATION OF OHIO

LIFTING JACK

Application filed May 16, 1928. Serial No. 278,267.

My invention relates in general to lifting jacks and more particularly to a jack of the double lift type, that is to say, a jack having a frame and a two-piece lifting member arranged in telescopic relationship. The main feature of jacks of this general type is that a jack having a low initial or collapsed height to accommodate the low front axle of modern automobile construction, especially when the tire is deflated, may be extended through a lifting range sufficient to accommodate the relatively high rear axle of the modern automobile especially when the tire is inflated, that is to say, the main feature of jacks of this type is the high ratio of fully extended height to collapsed height.

Such a jack is illustrated in my co-pending applications, Serial Number 242,697, filed December 27, 1927, and Serial Number 252,089, filed February 26, 1928, and my present invention contemplates the provision of a jack in which the double lift principle is embodied in a simpler, more rugged and more satisfactory construction than those illustrated and described in my above mentioned applications.

One of the important objects of my present invention is to provide, in a double lift jack, simple and positive means for preventing the rotation of the outer lifting member as it is raised or lowered in the jack frame upon the actuation of the operating member.

A further object of my invention is the provision of a friction device carried by an extensible member and having interlocking engagement with a grooved portion of the jack frame whereby the rotative urge, imparted to the extensible member through the threaded connection with the operating member may be counteracted.

Still another important object of my present invention is to provide in a lifting jack, a friction device of simple, rugged construction and positive action for preventing the relative rotation of an extensible member within a jack frame.

Numerous other objects and advantages of the invention will be apparent as it is more fully understood from the following description which, taken in connection with the ac-

companying drawing, discloses a preferred embodiment of the invention.

Referring to the drawing:

Figure 1 is a vertical cross-section taken through a jack embodying my present invention;

Figure 2 is a side elevation taken from the right in Figure 1 and showing the jack in partially and fully extended position;

Figure 3 is a horizontal cross-section taken substantially along the line 3-3 in Figure 1; and

Figure 4 is a horizontal cross-section taken substantially along the line 4-4 in Figure 1.

To illustrate my invention I have shown on the drawing a preferred embodiment of my invention comprising an integral support frame having a base 11 and a cylindrical sleeve 13 extending upwardly of the base. A bearing support 15 is arranged at the upper end of the cylindrical sleeve and has an upper portion extending thereover and carrying a bearing 17 aligned centrally over the upper end of the sleeve 13, strengthening webs 19 being arranged at the junction of the parts.

A beveled gear 21 having a hub 23 is rotatably mounted in the bearing 17 with its toothed periphery 25 extending outwardly to engage a co-operating driving pinion 27 carried on a stub shaft 29 journaled in a bearing 31 formed in the bearing support 15. End-play of the stub shaft is prevented by means of a shoulder 33 formed on the pinion. The stub shaft extends through the bearing and is provided with a collar having a central socket 35 which, in the illustrated embodiment, is square in cross-section. This socket is to accommodate the squared end of an operating handle (not shown) by which the rotation of the pinion and the gear may be accomplished

at a distance from the jack. The sleeve 13 provides a cylindrical channel 37 extending through the base to the upper end of the sleeve which is furnished to provide a bearing seat 39. The lower end of the bearing 17 and the bearing seat 39 are spaced apart sufficiently to allow the beveled gear 21 to be slid edgewise therebetween in order to place it in position to be arranged in the bearing 17, the hub 23 thereof sliding upwardly into place

100

within the bearing after the gear has been positioned edgewise therebeneath as aforesaid. The gear 21 is supported in position by means of a roller bearing 41 which may be set edgewise in position upon the bearing seat 39 underneath the gear after the latter has been arranged in position. The roller bearing 41 is provided with a central aperture 43 of equal diameter to the channel 37 and forming, when in position, a continuation thereof.

In the illustrated embodiment the extensible or lifting members comprise an inner shaft 45 having external threads 47 extending throughout its length, and an outer sleeve 49 having an internally threaded portion 53 at its upper end and provided with external screw threads 51 throughout its entire length. The threads 51 are adapted to co-operate with internal screw threads 57 formed in the bore of the gear 21 so that upon rotation of the gear, the tubular extensible member 49 may be moved axially in the frame. The internal threads 53 are adapted to co-operatively engage the external threads 47 on the inner extensible member 45 so that upon rotation of the outer extensible member, the inner member being held against rotation, the latter will be easily extended with respect to the former. A stop or peg 59 is set in the groove of the threads 47 at adjacent the lower end of the inner extensible member 45 to engage the lower end of the threaded portion 53 when the inner member is in extended position to limit the relative axial movement thereof with respect to the outer extensible member 49. The inner member 45 is first assembled through the lower end of the outer sleeve member 49 by engaging the threads 47 and 53. After the shaft is thus assembled the sleeve 49 and shaft 45 are together inserted in the sleeve 13 through the lower open end thereof by sliding them longitudinally through the channel 37 and through the opening 43 in the roller bearing. The external threads 51 of the outer extensible member 49 are then mated with the internal threads 37 of the operating member or gear 21. After the members are thus arranged, a peg 61 is set in the groove of the threads 51 and adjacent the upper end of the extensible member 49 which peg, by engaging the upper surface of the gear 21, limits the downward axial motion of the extensible member 49. A load-carrying head 63 is finally rigidly secured to the upper end of the inner extensible member 45.

Upon rotation of the gear 21, the extensible elements 49 and 45, being in the collapsed position illustrated in Figure 1, the outer or tubular extensible member 49 will be raised by the co-operation of the threaded portions 57 of the gear and 51 of the extensible member, provided that the extensible member is prevented from rotating within the frame.

In order to prevent such rotation I have provided a novel friction device mounted at the lower end of the extensible member and having a friction connection therewith and an interlocking connection in a grooved portion 73 of the tubular member 13. This friction device comprises a collar 65 having a central opening 67 adapted to loosely fit over the lower end 69 of the outer extensible member 49, which is peened over as at 71, after the collar has been arranged on the end of the extensible member to keep the same in position. The collar is provided with outstanding ears 75 which are adapted to engage in a slot 77 formed in the longitudinally ridged portion 73 of the tubular frame portion 13. The collar is provided with circular apertures 79 diametrically disposed therein and in which the ends of spring members 81 are adapted to engage. These spring members are arranged to frictionally engage the lower end of the extensible member 49 and to prevent relative rotation of the collar 65 about the extensible member. The slot 77 formed in the tubular upright portion of the frame extends throughout the length of the channel 37 so that no matter what position the extensible member 49 may assume in the sleeve, the friction device will always interlockingly engage the frame to resiliently prevent relative rotation of the extensible member therein.

Operation

Upon rotation of the gear 21 the extensible member 49 is raised from collapsed position within the cylindrical channel 37 by the co-operation of the threads 51 and 57, the frictional connection between the extensible member 49 and the frame, by means of the springs 81 and the collar 65, preventing the rotation of the former with respect to the latter. When the outer extensible member 49 arrives at the position illustrated in Figure 2 of the drawing, a peg 83 which is set in the groove of the threads 51 at a point spaced from the lower end of the tube, engages the lower edge of the gear and provides a positive driving connection between the gear and the extensible member whereby the member 49 is rotated in spite of the frictional resistance furnished by the springs 81 and collar 65. Upon rotation of the outer extensible member 49, a load being supported upon the head 63 and preventing its rotation, the shaft 45 is projected upwardly through the tube by the co-operation of the threads 47 and 53 until the fully extended jack position illustrated in dotted lines in Figure 2 of the drawing is reached, at which point the peg 59 arranged at the lower end of the extensible member 45, engages the lower end of the threaded portion 53 of the outer extensible member and prevents further extension in an upward direction of the inner extensible

member 45. By reversing the rotation of the gear 21, the outer extensible member is first withdrawn into the sleeve until the pin 61 at the upper end thereof engages the upper end 5 of the gear, whereupon the inner extensible member 45 is retracted within the outer member 49 until the load-carrying head 63 engages the upper end of the member 49 in which position the jack is in fully collapsed condition. 10 It will be readily seen from the foregoing that the gear 21 provides an operating member comprising an internally threaded collar rotatably mounted in the frame and having threaded engagement with the outer extensible member. The novel friction device comprising the collar 65 and the springs 81, by engagement of its outstanding ears 75 in the groove 77 of the tubular frame portion 13, prevents the member 49 from rotating in the 15 frame and allows the gear to raise and lower the extensible member in the frame. The pegs 61 and 83 act not only to limit the axial movement of the extensible member with respect to the frame, but also provide a positive 20 driving engagement between the gear and the extensible member whereby the inner extensible member 45 may be axially moved with respect to the outer member. The peg 59 and the lower surface of the lifting 25 head 63 (or a peg similar to peg 59 set in the groove of the threads 47 at adjacent the upper end of the member 45) provide means for 30 limiting the relative movement of the inner extensible member 45 with respect to the outer member 49.

The construction and arrangement of the friction device provides a maximum amount of friction in a construction of extreme simplicity and specially adapted to economic 40 production, it being apparent that the collar 65 may be stamped from sheet metal and that springs 65 may be made from common spring stock by cutting off therefrom considerable 45 lengths and bending the same to the desired shape. No accurate machining of the parts is necessary, no auxiliary housings are necessary, and the construction is of such simplicity as to be well adapted for embodiment in a commercial article.

50 It is thought that the invention and many of its attendant advantages will be understood from the foregoing description, and it will be apparent that various changes may be made in the form, construction and arrangement of the parts without departing from the spirit and scope of the invention or sacrificing any of its material advantages, the form herein described being merely a preferred embodiment thereof.

55 Having thus described my invention, what I claim as new and desire to secure by Letters Patent is:

60 1. In an extension device, a frame, a lifting member arranged in said frame, an operating member rotatably mounted in said frame and

having threaded connection with said extensible member whereby the extensible member may be axially moved with respect to said frame upon rotation of said operating member, means for rotating said operating member, and a frictional device carried by said extensible member and engaging said frame whereby to prevent relative rotation of said extensible member with respect to the frame, said frictional device having a collar loosely mounted on and embracing said extensible member and a spring device carried by said collar and frictionally engaging said extensible member for preventing relative movement between the collar and the extensible member. 70 75 80

2. In an extension device, a grooved frame, a lifting member arranged in said frame, an operating member rotatably mounted in said frame and having threaded connection with said extensible member whereby the extensible member may be axially moved with respect to said frame upon rotation of said operating member, means for rotating said operating member, and a frictional device carried by said extensible member and engaging said frame whereby to prevent relative rotation of said extensible member with respect to the frame, said frictional device having a collar loosely mounted on and embracing said extensible member and a spring device carried by said collar and frictionally engaging said extensible member for preventing relative movement between the collar and the extensible member, said collar having a 85 90 95 projecting ear adapted to engage the grooved portion of said frame. 100

3. In an extension device, a grooved frame, a lifting member arranged in said frame for projection therefrom, an operating member 105 slidably mounted in said frame and having threaded connection with said extensible member whereby the extensible member may be axially moved with respect to said frame upon rotation of the operating member, and a frictional device comprising a collar loosely mounted to and embracing said extensible member and having a projecting ear adapted to engage the grooved portion of the frame, and friction means mounted to said collar and frictionally engaging said extensible member to prevent relative rotation therebetween. 110 115

4. A housing having a non-circular inner bore and having a rotatable driving member, a threaded sleeve projectable by the driving member, means comprising wire stock embracing the sleeve at the lower end, said means having portions interengaging with the non-circular portion of the bore to normally prevent rotation of the sleeve in the bore, and said means forming a yielding connection between the sleeve and the standard, whereby to permit the sleeve to rotate with the driving member. 120 125

5. A jack comprising a housing with a ver- 130

tical groove and a rotatable driving member, a hollow threaded sleeve adapted to be projected by the driving member, a friction brake operable between the lower end of the sleeve and the housing and having an outstanding portion slidable in the vertical groove, whereby to normally prevent relative rotation of the sleeve in the housing, said brake comprising a resilient wire carried by said sleeve and having frictional engagement with one of said members to permit rotation of said sleeve with the driving member.

6. An automobile jack comprising a hollow, upstanding housing provided with a vertical groove, and a rotatable driving member, lifting means projectable by said driving member and including a threaded hollow sleeve, means for yieldingly holding the sleeve from rotation relative to the housing, but yielding to permit said sleeve to rotate with the driving member and relative to the housing, comprising means embracing the lower end of the sleeve operable between the housing and the hollow sleeve, and shiftable in and longitudinally of the groove in the housing, said means including wire spring stock adapted to yield with respect to one of said members between which it operates to permit the sleeve to rotate with the driving member.

7. A housing having a non-circular inner bore, a rotatable driving member, a threaded sleeve projectable thereby, means embracing the sleeve at the lower end, said means having portions inter-engaging with the non-circular portion of the bore, said means forming a yielding connection between the sleeve and the standard, whereby to permit relative rotation of the sleeve in the standard when at the limit of its movement.

8. A lifting jack comprising a hollow standard, an exteriorly threaded outer screw member mounted in the standard, an inner screw member threaded in the outer screw member, means for elevating said screw members comprising an interiorly threaded rotatable collar engaging the threads of the outer screw member, means surrounding and carried by the lower end of the outer screw member and in yielding frictional engagement with the outer screw member, said last named means having an end portion slidably guided in the standard for yieldingly resisting rotational movements of the outer screw member.

9. In a lifting jack, a frame, a lifting screw arranged in said frame for projection and retraction therefrom, an operating member arranged in said frame and having cooperative engagement with said lifting screw to move the same in the frame, and means surrounding and carried by the lower end of the lifting screw and normally yieldingly urged to frictionally engage the lifting screw and having keyed connection with the

frame whereby to normally prevent relative rotation with respect to the frame while permitting the lifting screw to move longitudinally.

10. In an automobile jack a grooved frame forming a housing providing a vertical channel, a lifting member arranged in said channel for projection and retraction therefrom, an operating member comprising a collar threadingly engaging the outer surfaces of said lifting member, said collar being mounted in the frame at the upper end of the channel, means for rotating said collar and means normally preventing rotation of the lifting member with respect to the frame, said means including a member encircling the lifting member and having frictional engagement therewith and having a projection forming a splined non-rotative axially movable connection with the grooved portion of said frame and load engaging means carried by said lifting member.

11. In an automobile jack, a grooved frame forming a housing providing a vertical channel, a lifting member arranged in said channel for projection and retraction therefrom, an operating member comprising a collar threadingly engaging the outer surfaces of said lifting member, said collar being mounted in the frame at the upper end of the channel, means for rotating said collar and means normally preventing rotation of the lifting member with respect to the frame, but yielding to permit rotation of the lifting member when at the limits of its travel, said means including a member encircling the lifting member and having frictional engagement therewith and having a projection forming a splined non-rotative axially movable connection with the grooved portion of said frame, and load engaging means carried by said extensible member, said lifting member being formed as a hollow sleeve provided with internal screw threads and said load supporting member comprising a member threaded into the lifting member and having a load carrying head at its upper end.

In witness whereof, I have hereunto subscribed my name.
